(57) CLAIM

The ornamental design for a display screen with speakers as shown and described.

DESCRIPTION

FIG. 1 is a front, right, top perspective view of a display screen with speakers showing our new design in a first state in which two circular speakers are disposed at the front of a display panel for use in an audio mode;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right, top perspective view thereof in a second state in which the circular speakers are moved to both ends of the display panel;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a front, right, top perspective view thereof in a third state in which the circular speakers are moved to the rear of the display panel for use in a video mode;

FIG. 16 is a front view thereof;

FIG. 17 is a rear view thereof;

FIG. 18 is a left side view thereof;

FIG. 19 is a right side view thereof;

FIG. 20 is a top plan view thereof; and,

FIG. 21 is a bottom plan view thereof.

The broken lines depict portions of the display screen with speakers that form no part of the claimed design.

1 Claim, 21 Drawing Sheets
